UNITED STATES PATENT OFFICE

166,501

TABLECLOTH OR SIMILAR ARTICLE

Nessim Shalom, Brooklyn, N. Y.

Application October 23, 1951, Serial No. 17,073

Term of patent 3½ years

(Cl. D92—26)

To all whom it may concern:

Be it known that Nessim Shalom, a citizen of the United States of America, and resident of Brooklyn, in the county of Kings and State of New York, has invented a new, original, and ornamental Design for Tablecloth or Similar Article, of which the following is a specification, reference being had to the accompanying drawing, forming part thereof, in which

The figure is a plan view of a tablecloth, embodying my new design.

I claim:

The ornamental design for a tablecloth or similar article, substantially as shown.

NESSIM SHALOM.
